UNITED STATES PATENT OFFICE.

ALFRED G. HOLCOMBE, OF DANIELSONVILLE, CONNECTICUT, ASSIGNOR TO
DANIEL K. COLBORN, (TRUSTEE,) OF NEW YORK, N. Y.

ELECTRIC-ARC LAMP.

SPECIFICATION forming part of Letters Patent No. 269,417, dated December 19, 1882.
Application filed February 21, 1881. (No model.)

To all whom it may concern:

Be it known that I, ALFRED G. HOLCOMBE, of Danielsonville, Windham county, State of Connecticut, have invented certain new and useful Improvements in Electric-Arc Lamps, of which the following is a specification.

In application, No. 6,480, for Letters Patent filed by me April 2, 1880, are shown and claimed as a regulating device for electric currents two solenoids so arranged and connected as to be mutually attractive when a to-and-fro electric current is caused to pass through them, and in combination with the mechanism of an electric lamp adapted to form and maintain an arc between the ends of carbon rods.

This invention has for its object the further practical application of the principle embraced by the law established by Ampère—viz., the mutual attraction of parallel electric currents flowing in the same direction and their mutual repulsion when flowing in opposite directions. I place two flat coils of insulated wire in close proximity, parallel, face to face, each carried by a suspended bar provided at their lower ends with carbon rods whose free ends are in contact when no electric current is passing through the coils, but are caused to separate as soon as a to-and-fro electric current traverses the coils, and so allow said current to form an electric arc between their ends, the carbon rods and the suspended bars being in the circuit between the two flat coils.

A speed-regulating device to prevent the too sudden separation of the carbons, and an adjustable stop device to be used in combination therewith, or separately, also form a part of this invention, which further embraces a shunting device adapted to short-circuit the to-and-fro current from one of the coils and the arc when the carbons are consumed to within a short distance of their holding-sockets, and cause the current to flow through an adjoining lamp provided with carbon rods adjusted ready to produce an electric light.

In the accompanying drawings, forming part of this specification, Figure 1, Sheet 1, is a front elevation of my improved electric lighting apparatus with the shunt and speed-retarding devices. Fig. 2, Sheet 1, is a similar

view in section minus the shunt and speed-retarding devices. Fig. 3, Sheet 1, is a sectional elevation taken at right angles to the view Fig. 1. Fig. 4, Sheet 1, is a plan. Fig. 5, Sheet 1, is a transverse section of the speed-retarding device. Fig. 6, Sheet 2, is a modification of the upper part of the apparatus in section. Fig. 7, Sheet 2, is a side elevation of the same. Fig. 8, Sheet 2, is a front elevation of another modification; and Fig. 9, Sheet 2, is a side elevation of the same.

The two carbon rods *a* and *a'* are suspended side by side and secured respectively to the bars *b* and *b'* by means of the clamps *b*² *b'*². The upper ends of the bars *b* and *b'* are respectively connected to the disks of insulating material, *c* and *c'*, which carry on their adjacent faces the flat coils of insulated wire *d* and *d'*. The disks *c* and *c'* are fastened to the T-pieces *e* and *e'*, provided with the screws *e*² *e'*², the points of which rest in cavities formed in the ends of the screws *e*³ *e'*³, screwed through the horizontal arms of the brackets *f* and *f'* on the lower side of the plate of insulating material *g*, by means of which the lamp is supported in the ordinary manner. The cavities in the ends of the screws *e*³ *e'*³ are provided with cups, of glass or other suitable insulating material, or the screws themselves are insulated where they pass through the brackets *f* *f'*. The upper ends of the supporting-screws *e*² *e'*² are prolonged, so that they will come in contact with the plate *g* or flanges of the brackets *f* *f'* before their pointed ends clear the cavities in the screws *e*³ *e'*³, thus preventing the separation of the coils and carbon-carrying bars from the rest of the lamp when it is moved about. The pointed supporting-screws *e*² *e'*² permit of the movement of the carbons to and from one another with the least possible amount of friction, and also allow the carbons to be adjusted to bring their ends in line.

To counterbalance the coils and the bars *b* and *b'* so as to bring the ends of the carbon rods *a* and *a'* in contact when no current is passing through the lamp, as shown at Fig. 2, the adjustable weights *b*³ *b'*³ are secured to rods projecting from the outer sides of the bars *b* and *b'*.

I prefer to use with this class of electric lighting apparatus thin flat rods of carbon, as shown, with the object of causing the same to be perfectly consumed.

- 5 The carbon rods a and a' are set at an angle to one another by means of their clamping-sockets b^2 b^2 being hinged to the ends of the rods b' and b , and they are held in position when the angle is determined by tightening the 10 screws of the hinge-joints. The object of setting the carbons at an angle is to cause the length of the arc to increase, and so increase its resistance as the carbons become shorter, and so decrease in resistance, the angle of the carbons being such that the increment of the 15 arc-resistance equals the decrement of the carbon-resistance, the resistance of the lamp thereby remaining constant as the carbons are consumed.
- 20 The electric current enters the binding-post h , and passes, by the wire h' , to the T-piece e , which is connected thereto as near the center of oscillation as possible, so as not to affect the free movement of the bar b . From the T-piece 25 e it enters the coil d at its outer end, and from the center to the bar b , down the bar b to the end of the carbon rod a , which is now in contact with the carbon rod a' , up the carbon a' and bar b' to center of the coil d' , from the 30 outer end of coil d' to the center of oscillation of the T-piece e' , through the wire i' to binding-post i , and back to the generator by conductor i^2 . As the current passes through the two flat parallel coils d and d' in opposite directions, said coils are caused to separate, and 35 so the arc is produced between the ends of the carbon rods.

The lamp will operate with a continuous current; but I find that a much more energetic 40 action is produced between parallel conductors with a to-and-fro current.

Instead of arranging the parallel conductors as flat circular spirals, they may be elliptical or rectangular in form, and they will operate 45 as well when one is slightly concave and the other correspondingly convex.

The extent to which the carbon rods are allowed to separate is governed by the set-screw j , which passes through an arm on the bar b' 50 and butts against an insulated plug on the bar b . The current employed is sufficiently powerful to always keep the screw j against the plug on the bar b when the arc is of proper length, and this stop prevents the arc breaking, as might occur should the repulsive action 55 of the current in passing through the coils d and d' be allowed to act on them unrestrictedly. To also govern this movement of the carbon rods, I propose in some cases to use a 60 speed-retarding device such as is shown at Figs. 1, 4, and 5, which consists of a cylindrical case, k , provided with two or more fixed division-plates, k' k' , placed radially therein, and a shaft, l , with as many wings as there are division-plates k' k' .

On the top of the shaft l a double-crank arm is secured, the ends of which are connected to

the upper ends of the levers m and m' by means of the links n and n' . The levers m and m' are pivoted to downwardly-projecting 70 arms m^2 m^2 , and their lower ends are provided with set-screws, which butt against insulated plugs o o on the bars b and b' , they being so held by the springs o' o' . In the case k is placed a suitable fluid—as oil, glycerine, &c.— 75 which offers resistance to the wings on the shaft l when the bars b and b' are being separated. The speed-retarding device may be used in connection with the stop j , or either 80 may be used independently of the other.

To the bar b' is secured the spring p , with insulating material between them. The lower bent end of the spring is provided with a refractory metal and bears against the carbon rod a' , and when the carbon rods are consumed 85 up to this bent end of the spring it is released, and the pin p' makes contact with the bar b , thereby short-circuiting the current from the carbons and the flat coil d' and allowing it to pass to the binding-post h of the adjoining 90 lamp, Fig. 2, by the conductor p^2 . The current, after actuating the parts of lamp Fig. 2, to produce an arc between the ends of its carbons in a similar manner to that described as occurring in lamp Fig. 1, which is now inoperative, passes back to the generator from the binding-post i , which is connected to the conductor i^2 of the first lamp.

Any number of lamps may be automatically 95 successively lighted by providing them with this shunting device, which is also adapted to be applied to other lamps without any material changes in its construction.

Instead of utilizing the repulsive action of two parallel electric currents flowing in opposite directions to cause the carbon rods to separate, as above described, the attractive action of the currents by causing them to flow through the parallel coils in the same direction may be utilized to separate the carbons 105 and form the arc between their ends by the disposition of the coils d and d' shown in Figs. 6 and 7. The frames r and r' , pivoted 110 above the plate g , carry the coils d and d' , and their tail-pieces r^2 r^2 are connected to the suspended bars b and b' by the link r^3 r^3 . The lower part of the lamp is not shown in these 115 views, its connection with the upper part being understood from the description of the preceding views. The coils d and d' are in this 120 case formed of flat ribbons of copper, with ribbons of paper or other suitable insulating material between the successive turns and on the outside of the coiled copper ribbons, which are then placed in the circular parts of the frames 125 r and r' . This manner of forming the coils is for some reasons preferable to coiling insulated wire on disks of non-conducting material, and will probably be the method employed by me in constructing lamps on this principle. The 130 connections are made to the binding-posts h and i by wires, as shown. The arrows indicate the direction of the current in passing through the coils d and d' and the bars b and b' .

Figs. 8 and 9 show another modification, in which the parallel coils are so arranged in relation to one another that the action of the current in passing through them causes them to move to or from one another in a lateral direction; instead of with a direct axial movement. The carbon-carrying bar b' is fixed rigidly to the plate g , and the bar b is pivoted thereto by the screws s in such a manner as to have no electrical connection between the bars b and b' . The coils d and d' are held in circular frames of the bars b and b' , which are twisted at their lower parts so as to bring the carbon rods a and a' at right angles to the position they occupy in Figs. 1, 2, and 3 in relation to the coils d and d' . The current enters the outer end of the coil d by the conductor t , and from its inner end to the bar b by the conductor t' , down the bar b , up the bar b' to the center of the coil d' by the conductor b^3 , and out of the coil d' , back to the generator by the conductor t^4 .

The invention is shown as embodied in a hanging lamp. It may be applied to other styles of lamp to form and maintain an electric arc between the ends of carbon rods, and in all cases one of the carbon-carrying bars may be stationary, if desired, as shown at Figs. 8 and 9.

I do not claim broadly the combination, with the carbon-carrier of an electric lamp, of means for shunting the current around the lamp when the carbon rods are consumed, as such device is shown in English Patent No. 5,157 of 1879.

It is obvious that the two parallel coils d d' are adapted to be used in other forms of electric lamps, and the reciprocal substitution of them and the solenoids referred to at the commencement of this specification may be made in a manner well understood by those familiar with the art of electric lighting.

Any one or more of the various devices herein shown combined, constituting an electric lighting apparatus, may be used independently, and I do not wish to confine myself to the

particular construction and arrangement of devices shown; but

What I claim, and desire to secure by Letters Patent, is—

1. In an electric-arc lamp adapted to utilize a to-and-fro electric current, in combination, two depending bars adapted to be moved freely to and from one another, two flat metal coils secured to said depending bar, arranged face to face, and two carbon rods secured to the lower ends of the depending bars, the whole being arranged in single circuit, substantially as and for the purpose hereinbefore set forth.

2. In an electric lighting apparatus, the combination of two suspended bars, each provided at its lower end with an adjustable carbon-holding socket, whereby the carbon rods held by them may be arranged in such angular relation to one another that the sum of the resistance of the carbon rods and the arc formed between their ends shall be a constant quantity, as set forth.

3. In combination, the pivoted bars b and b' , the flat coils of insulated wire d and d' , the carbon rods a and a' , and the adjustable stop j , substantially as and for the purpose hereinbefore set forth.

4. In combination, the speed-regulator k l m , n , the pivoted bars b and b' , the flat coils of insulated wire d and d' , and the carbon rods a and a' , substantially as and for the purpose set forth.

5. In combination, the spring p , pin p' , carbon rod a' , bar b , constituting a shunting device of an electric lamp, and the conductor p^2 , connecting the spring p to the binding-post of an adjoining lamp, substantially as and for the purpose set forth.

In witness whereof I have hereunto set my hand this 15th day of February, 1881.

ALFRED G. HOLCOMBE.
